UNITED STATES PATENT OFFICE.

WALTER J. MC VICKER, OF MINNEAPOLIS, MINNESOTA, ASSIGNOR TO MINNEAPOLIS STEEL & MACHINERY COMPANY, OF MINNEAPOLIS, MINNESOTA, A CORPORATION.

FRAME FOR TRACTION-ENGINES.

1,173,594.

Specification of Letters Patent. Patented Feb. 29, 1916.

Application filed September 24, 1912. Serial No. 722,034.

To all whom it may concern:

Be it known that I, WALTER J. MC VICKER, of Minneapolis, Hennepin county, Minnesota, have invented certain new and useful 5 Improvements in Frames for Traction-Engines, of which the following is a specification.

The object of my invention is to provide a strong, substantial frame to support the 10 engine and operating mechanism of the machine.

A further object is to provide a frame of comparatively simple construction and one which will be extremely rigid in proportion 15 to its weight and dimensions.

Other objects of the invention will appear from the following detailed description.

The invention consists generally in various constructions and combinations, all as 20 hereinafter described and particularly pointed out in the claims.

In the accompanying drawings forming part of this specification, Figure 1 is a side elevation, partially in section, of a traction 25 engine embodying my invention, Fig. 2 is a perspective view of the frame, looking toward the rear end thereof, Fig. 3 is a perspective view, looking toward the side of the machine.

30 In the drawing, 2 represents the rear axle, having carrying wheels 3, and 4 the forward axle having carrying wheels 5. 6 is the engine, supported upon a girder-built frame which forms the subject matter of my invention and which I will now describe in detail.

The main frame, or upper portion, consists of side rails 7 of channel bar, having forward and rear cross bars 8 and 9 and an 40 intermediate bar 10, all of said bars being securely riveted to the flanges of the channel bars. The under frame consists preferably of angle bars 11 having their rear portions parallel substantially with the channel bar 45 7 and connected therewith by upright angle bar braces 12. The forward portions of the angle bars 11 are upwardly turned and have their forward ends rigidly secured to the channel bars 7. Between the upper and 50 under frames I provide steel plates 13, riveted to the said frames and forming a plate girder on each side of the frame. Cross braces 14 are provided between these plate girders and suitable braces 15 con-

nected the opposite horizontal flanges of the 55 angle bars 11.

The arrangement of braces between the girder plates provides for an extremely rigid frame to which the motor transmission system and the radiator are bolted. A bolster 60 16, triangular in form, is secured to the forward portion of the girder frame, with its lower end resting on the forward axle. An angle bar 17 is provided with a series of holes 17' therein and with braces 18 65 which extend forwardly and also have holes therein to receive bolts 19 mounted in a draw-bar 20. This draw-bar is attached to one of the cross braces of the frame by a spring connection 20'. The angle bar 17 and 70 the bars 18 form a detachable plow hitch, the holes 17' allowing a series of plows to be connected to this angle bar in the rear of the machine.

Rails 21 are secured to the girder plates 75 and extend rearwardly therefrom and rest upon a cross bar 22. Upon these rails 21 a platform 23 for the operator of the machine is mounted.

The rear axle 2 passes through openings 80 24 provided in the girder plates, as shown in Fig. 1.

The gasoline tank of the power plant may be secured to the girder frame in any suitable manner, but I prefer to provide straps 85 25 passing over the tank and having their ends secured in the upper horizontal flanges of the channel rails. By tightening the nuts on the ends of the straps the tank may be rigidly secured to the top of the frame. 90

I claim as my invention:—

1. A traction engine frame comprising upper parallel side rails, lower parallel side rails having upwardly turned forward portions secured to said upper rails, upright 95 braces interposed between the rear portions of said upper and lower side rails, girder plates secured to said side rails and said braces, cross bars interposed between the opposite side rails and between 100 said girder plates, a rocker provided at the forward end of said side rails, and forward and rear axles having carrying wheels supporting said rocker and the rear portion of said frame. 105

2. In a traction engine, a girder-built frame comprising upper and lower members, the forward portion of said lower member

being upwardly turned and connected to said upper member, the rear portions of said members being substantially parallel with one another, girder plates having their upper and lower portions secured respectively to said members, and suitable braces for said members and girder plates.

3. A built-up girder frame comprising an upper member, a lower member having its forward portion upwardly turned and secured to said upper member, girder plates having their upper and lower portions secured respectively to said upper and lower members, braces between said girder plates, 15 a bolster arranged beneath the forward portion of said members, a forward axle whereon said bolster is mounted, and a rear axle projecting through openings provided in the rear portion of said girder plates.

20 4. In a traction engine, a girder-built frame having a substantially flat top forming an engine bed, a bolster arranged beneath the forward portion of said frame, the rear portion of said girder-built frame

having openings therein, and a rear axle projecting through said openings.

5. A traction engine frame comprising upper parallel channel bar rails, lower parallel angle bar rails having their rear portions parallel substantially with said channel rails and their forward portions upwardly turned and secured to said channel rails, girder plates extending from end to end of said upper and lower rails and secured thereto, the rear portions of said girder plates having bearings for the rear axle therein and the forward portion of said channel bar rails having a rocker depending therefrom, and suitable braces interposed between the opposite rails and 40 girder plates.

In witness whereof, I have hereunto set my hand this 18th day of September, 1912.

WALTER J. McVICKER.
